UNITED STATES PATENT OFFICE.

WILLIAM LAWRENCE, OF NEW YORK, N. Y., ASSIGNOR TO THE UNIVERSAL SURFACE ELECTRIC RAILWAY COMPANY, OF WEST VIRGINIA.

ELECTRIC-RAILWAY SYSTEM.

SPECIFICATION forming part of Letters Patent No. 605,317, dated June 7, 1898.

Application filed December 1, 1897. Serial No. 660,348. (No model.)

To all whom it may concern:

Be it known that I, WILLIAM LAWRENCE, a citizen of the United States, residing at New York, in the county of New York and State of New York, have invented certain new and useful Improvements in Electric-Railway Systems; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

The invention relates to surface-contact electric railways in which the circuit is normally interrupted at intervals along the track. This circuit is closed and opened at points under the car by means of a magnetic device carried upon the car.

Figure 1 is a diagrammatic view embodying my invention. Fig. 2 is a plan of the railway-track. Fig. 3 is a cross-section of the track through one of the junction-boxes. Fig. 4 is a longitudinal cross-section of a junction-box. Fig. 5 is a detail perspective of the switch mechanism.

1 represents a sectional surface-contact feeder-rail. 2 are pole-pieces on the under side of rail 1. This rail 1 is preferably broken at 35 and also between the poles 2, or, what is substantially the same thing, a piece of diamagnetic metal 36 is inserted between the sections 1 at the poles 2.

3 is a junction-box inclosing the pole-pieces. 4 is an oscillating shaft journaled in box 3. 5 is an armature on shaft 4, disposed between the pole-pieces 2.

6 is a switch mechanism normally open. 7 is the switch-box within the junction-box. 8 is a weighted arm upon shaft 4, normally acting to keep the switch 6 open. 9 is a dynamo. 10 is a feed-wire therefrom, and 11 a return-wire thereto.

12 is a feed-wire to switch 6. 13 and 14 are feed-wires leading from switch 6 to contact-rails 1. 15 and 16 are the ordinary track-rails. In-

stead of the usual bonding of these rails to 50 return the circuit, the rail-sections 15 are not directly connected electrically, but return-wires 17 and 18 are led from said rails to the switch 6.

19 is a return-wire from switch 6 to the return-wire 11 and dynamo 9.

The car carries a current-collector 20, having, preferably, rolling contacts 21 and electromagnets 22 electrically connected thereto.

23 is a wire leading from collector 20 and magnets 22 to the car-motor 24.

25 is a wire leading from the motor to the track 15 through one of the car-wheels.

In operation the current flows from dynamo 9, through feeder 10, branch wires 12, 65 to switches 6. When the magnets of the collector 20 reach the feeder-rail sections 1, substantially opposite the pole 2, and make contact therewith, the magnets 22 are energized from the preceding section and a magnetic 70 flux enters the pole-pieces 2, causing the armature 5 to find its relative poles. Shaft 4 is thereby oscillated and electrical connection established between wire 12, feeder 10, and wires 13 and 14 to the adjacent feeder-sections 1 through contact 26 of switch 6 and between wires 17 and 18, leading from track-sections 15 to wire 19 of return-wire 11, through contact 27 of the switch. The current thereupon flows through switch 6 to sections 1, where 80 their respective armatures are actuated, to contacts 21, collector 20, wire 23, to motor 24, and from the motor by wire 25 and car-wheel to rail 15, to wires 17 and 18, switch 6, wire 19, wire 11, to dynamo 9. 85

The current is broken through sections 1 when the collector passes from contact therewith, the pole-pieces 2 become demagnetized, and the weighted arm 8 causes armature 5 to swing back, thereby breaking all connections through switch 6 and rendering all sections not under the car dead and harmless. The armature 5 thus held by the magnets 22 until the current-collector passes from each section, after being excited, is due to the armature coming into contact with the poles 2 and forming a magnetic catch. 90

Junction-box 3 has a hand-hole provided

with a cover 28, a drain 29 to the sewer, openings for the feed and return wires 10 and 11, supports for the switch-box 7 and shaft 4, and insulated bearings 30 for the feeder-sections 1.

Some of the track-rail sections 15 may be longer than the sections 1, and those switches adjacent the longer sections 15 may have only one return-wire 31 instead of two returns 17 and 18.

This system will operate in connection with a continuous return through the usual bonded track-rails, if desired, in which case wires 11, 17, 18, 19, and 31 may be omitted; but I prefer the described system as safer and surer.

What I claim as new, and desire to secure by Letters Patent, is—

1. In a surface-contact electric railway, the combination of a moving vehicle, field-magnet poles located between the tracks at suitable intervals, an armature mounted for movement between the faces of each pair of poles, and a magnet carried by the moving vehicle supplying a magnetic flux to the field-poles for moving the armature.

2. The combination of feeder-rail sections, pole-pieces upon each of said sections, an armature pivoted at its center and disposed between the adjacent ends of said pole-pieces normally at right angles to said sections, wire connections, and a source of energy, whereby the armature is caused to swing into line with said sections and find its relative poles.

3. The combination of feeder-rail sections, pole-pieces upon said sections, an armature hung between said pole-pieces, and means for energizing said sections, whereby the armature is caused to swing into line with said sections.

4. The combination of a sectional track-rail, feeder-rail sections, pole-pieces upon said sections, an armature pivotally hung between said pole-pieces, an oscillating shaft upon which the armature is hung, means for normally holding the armature at right angles to said sections, switch-pieces upon said shaft and oscillating therewith, fixed switch-pieces, wires leading from the switch-pieces to adjacent sectional track-rails, a source of electrical energy, and wires leading therefrom to

the oscillating switch-pieces upon the armature-shaft.

5. The combination of feeder-rail sections, pole-pieces upon said sections, a centrally-pivoted armature hung between said poles, an oscillating shaft upon which the armature is hung, a switch-piece upon the shaft, wire connections, a source of energy for energizing the feeder-rail sections and causing the armature to find its relative poles and actuate the switch, and a car carrying a motor and a current-collector.

6. In an electric-railway system the combination of a junction-box having a top provided with a cover and a seat for the feeder-section, an oscillating shaft mounted therein carrying an armature and a switch, and a secondary box within the junction-box enclosing the switch.

7. In an electric-railway system, a junction-box having a seat for a feeder-rail extending longitudinally across one side of the same, a secondary box within the junction-box enclosing a switch mechanism, and a removable cover for the junction-box.

8. A junction-box for surface-contact railways provided with a seat at one side for the surface contact, a cover-plate alongside thereof, and having a removable secondary switch-box within the junction-box, a shaft within the secondary switch-box carrying a switch, and extending out across the junction-box and carrying an armature.

9. A junction-box for surface-contact railways provided with a seat at one side for the surface contact, a cover-plate alongside thereof, a secondary switch-box within the junction-box having a removable cover lying under the removable cover of the junction-box, a shaft extending across the junction-box and through the secondary box, having a switch within the secondary box, and an armature within the junction-box.

In testimony whereof I affix my signature in presence of two witnesses.

WILLIAM LAWRENCE.
